J. H. DOUTHIT, OF ALBANY, OREGON.

Letters Patent No. 61,408, dated January 22, 1867.

IMPROVEMENT IN GANG PLOUGHS.

The Schedule referred to in these Letters Patent and making part of the same.

TO ALL WHOM IT MAY CONCERN:

Be it known that I, J. H. Douthit, of Albany, Linn county, Oregon, have invented a new and improved Gang Plough; and I do hereby declare that the following is a full, clear, and exact description thereof, which will enable others skilled in the art to make and use the same, reference being had to the accompanying drawing, forming part of this specification, in which—

Figure 1 is a plan or top view of my invention, partly in section.

Figure 2, a side sectional view of the same, taken in the line $x x$, fig. 3.

Figure 3, a transverse vertical section of the same, taken in the line $y y$, fig. 2.

Similar letters of reference indicate like parts.

This invention relates to a new and improved gang plough, and it consists in a novel construction and arrangement of parts, as hereinafter fully shown and described, whereby the operator has full or perfect control over the ploughs.

A A represent two parallel bars, connected at one end by cross-bars B B, and having an axle, C, bolted to their upper sides. D D are the wheels on said axle, and E is a draught-pole, secured between the cross-bars B B. F F represent two parallel plough beams connected by cross-bars a , and having each a plough, G, attached, one a little in advance of the other. The front cross-bar, a , of the plough beams F F, has its ends extending through the beams F F, and is fitted in slides H H, the latter working between suitable guides, e e, at the inner sides of the bars A A. One of these sides has a foot-lever, I, attached to it, said lever extending forward so that its front end may be readily acted upon by the foot of the driver from his seat J, for the purpose of elevating, when necessary, the front ends of the plough beams; and the other slide, or both, in fact, are perforated with a series of holes, through any of which pins, K, pass to hold the plough beams at any desired height, and consequently regulate the depth of the penetration of the ploughs as may be desired. The driver's seat, J, is secured to parallel horizontal bars, d d, supported by uprights, e e, from the bars A A. L is a windlass, the bearings of which are in the bars d d. This windlass has a cord or chain, M, attached, which is connected to the outer cross-bar, a , of the plough beams F F, and to one end of the shaft of windlass L a crank, N, is attached, and a ratchet, O, also keyed upon it, into which ratchet a pawl, P, catches. To the windlass, L, there is also attached a cord or chain, M', which is wound around the shaft of the windlass in an opposite direction to the cord or chain M, and passes around a pulley, f, in the rear end of a bar, Q, secured in the framing of the machine, and then passing upward is attached to a cross-bar, a , of the plough beams. This cord or chain, M', serves to keep the ploughs G G in the ground, as it holds the plough beams F F down; and as said cord or chain is wound upon the windlass L, in a reverse direction to the chain M, it will be seen that when the windlass L is turned, in a direction to wind the chain M upon it, the chain M' will be unwound from it, and *vice versa*. Hence it will be seen that by turning the windlass L, the ploughs may be elevated out of the ground when not required to operate, and be lowered into the ground when required for use, without being in the least interfered with by the chain M'. The windlass L is designed to be turned by hand, and is used only when the ploughs are elevated permanently, as, for instance, in drawing the device from place to place. The ploughs are raised temporarily by means of a windlass, R, one end of which has its bearing attached to one of the bars d, the other end having its bearing in a slide, S, to which a lever, T, is attached. On this windlass shaft, at the outer side of the slide S, there is keyed a pulley, U, having a ratchet V attached to its inner side, and around the pulley U and a pulley W attached to one of the wheels, D, a belt h passes. X is a pawl which engages with the ratchet V, and has a spring, i, acting upon it to keep it in contact with the ratchet V, and a lever, Y, attached to it for the purpose of throwing the pawl out or off from the ratchet when necessary, (see fig. 2.) The belt h is to be tightened at any time by actuating the lever T, so as to rotate the windlass R, and raise the plough beams F F. Through the medium of a cord or chain A*, rendered slack by releasing the lever Y, the windlass R is rendered inoperative. The pawl X serves to prevent any casual reverse movement of the windlass R.

From the above description it will be seen that the ploughs are under the complete control of the operator or driver, and may be readily operated or manipulated by him. The draught-pole may be shifted laterally between the bars B B, according to the direction of the line of draught required.

Having thus described my invention, what I claim as new, and desire to secure by Letters Patent, is—
1. The attaching of the plough beams F F to slides H H, fitted between suitable guides c c, at the inner sides of the bars A A, in connection with the foot-lever I, attached to one of the slides H, and the pin K passing through any of a series of holes in the other slide H, substantially as and for the purpose set forth.

2. The windlass L, having the cords or chains M M' attached, and the latter connected to the plough beams F F, to operate in the manner substantially as and for the purpose specified.

3. The windlass R, having a cord or chain A* attached, which is connected to the plough beams F F; one of the bearings of the windlass being fitted in a slide S, and having a pulley U on one end, around which and a pulley W, on wheel D, a belt h passes, in combination with the lever T attached to slide S, all being arranged to operate in the manner substantially as and for the purpose set forth.

J. H. DOUTHIT.
